Primary Examiner — Cynthia Underwood(74) *Attorney, Agent, or Firm* — Young & Thompson(57) **CLAIM**

The ornamental design for a attachment device, as shown and described.

DESCRIPTION

FIG. 1 is a front, right side and top perspective view of an attachment device showing the new design;
 FIG. 2 is a front elevation view thereof;
 FIG. 3 is a rear elevation view thereof;
 FIG. 4 is a left side elevation view thereof;
 FIG. 5 is a top plan view thereof;
 FIG. 6 is a bottom plan view thereof; and,
 FIG. 7 is a front, right side and top perspective view thereof,
 shown reduced in scale, as included in a safety device for a
 personal fall protection.

The broken lines shown in FIGS. 1-4, 6, and 7 represent unclaimed subject matter and form no part of the claimed design.
